UNITED STATES PATENT OFFICE.

EDWARD D. WOODS, OF HARTFORD, CONNECTICUT, ASSIGNOR TO THE NEW PRODUCTS CO., OF HARTFORD, CONNECTICUT.

POLISHING-WHEEL.

1,186,058.

Specification of Letters Patent.

Patented June 6, 1916.

Application filed October 29, 1914. Serial No. 869,195.

To all whom it may concern:

Be it known that I, EDWARD D. Woods, a citizen of the United States, residing at Hartford, in the county of Hartford and 5 State of Connecticut, have invented certain new and useful Improvements in Polishing-Wheels; and I do hereby declare the following to be a full, clear, and exact description of the invention, such as will enable others skilled in the art to which it app- 10 pertains to make and use the same.

My invention relates to an improved polishing wheel having an annular rim supported on a spiral spring band whereby a 15 resilient action is imparted to the rim under the polishing pressure.

Referring to the drawings:—Figure 1 represents a side elevation of the improved wheel; Fig. 2, a side elevation with one of 20 the side plates removed showing the interior of the wheel and the manner of supporting the annular rim on the spiral spring; Fig. 3 is a side elevation showing the interior of the wheel with an inflated tube underlying 25 the spiral spring to give an increased resistance to the polishing pressure and is adapted particularly for heavy work; Fig. 4 is a broken detail view of the spiral spring in closed, confined working position; Fig. 5 30 is a detail view of the spiral spring unconfined and fully opened; Fig. 6 is a broken central sectional view of a part of the wheel shown in Fig. 3; Fig. 7 is an enlarged central sectional view on line 7—7 35 of Fig. 1; Fig. 8 is an enlarged broken central sectional view of the side plates, spring and T-shaped annular rim; and Fig. 9 is a detail reduced side elevation of the T-shaped annular rim.

40 The object of my invention, before mentioned, is to construct a resilient polishing wheel so that it will hug the work more closely and give better and quicker results than a solid unyielding wheel.

45 Referring to the drawings for a detail construction of my improved wheel, 1 and 2 are side retaining plates, the former having the hub 3 adapted to receive an arbor (not shown), and the latter is mounted on 50 a reduced portion of the hub as shown in Fig. 7. These plates are held together by collars (not shown) on the arbor.

46 is an annular rim made of felt, duck or 55 duck and rubber or other like material coated with emery or other like abrasive mate-

rial 5. This rim is mounted directly on the spiral spring 6, which spring may be made of any number of coils desired to give the proper resiliency required for any particular work. Tension is first stored up in the 60 spring by coiling it up into a smaller compass than the inside of the rim, so that, when inserted and released, the stored up tension will cause the spring to hug closely the inside of the rim, Figs. 2, 3, 6, 7 and 8, and 65 thus form a flexible support therefor. The spring is made of thin spring metal to give it the desired flexibility, and to render it available for the desired purpose it must be capable of being coiled so as to expand forc- 70 bly against the rim.

The center of the side plates is stiffened by the integral arm portions 7, and their flanged edges 8 are adapted to enter the circumferential grooves 9 of the annular 75 rim, the coiled spring normally forcing the rim against these flanges, and these grooves are wide enough to allow the inward movement or depression of that portion of the periphery of the rim brought directly 80 against the article to be polished. The abrasive surface of the T-shaped rim 4, Figs. 8 and 9, being narrower than the abrasive surface of rim shown in the other 85 views, dispenses with the circumferential groove 9.

For grinding, or very heavy work, the number of coils may be increased or the pneumatic tube 10, Figs. 3 and 6, may be interposed between the spirally coiled spring 90 and the interior circumferential support 11, which support may constitute a separate piece or it may be integral with the stationary side plate 1 as shown.

To provide expeditious means for balancing the wheel, I employ the adjustable weights 12 mounted on the threaded studs 13, to be secured in any of their adjusted positions by the jam nuts 14. Any suitable weights that can be readily adjusted and 95 properly located can be used.

The high peripheral speed of polishing and grinding wheels renders it impossible to maintain the work against solid wheels without more or less jumping or trembling resulting in a wavy uneven finish on the surface of the work. This tendency to tremble is entirely overcome in a cushion wheel as above described, for instead of jumping, the wheel will hug the work with increased te- 105 110

nacity as the applied power or force is increased. The centrifugal force will have a tendency to spread or open the coils of the spiral spring as the speed of the wheel increases and thus maintain the resiliency, flexibility and balance of the wheel under all circumstances; a result that can only be obtained with a spiral spring contacting the entire inner circumference of the rim. While the rim could be made of solid material mounted on the spiral spring, better results can be obtained when the rim is made of duck, felt or other like flexible material combined with the spiral spring, as it will hug the work more closely.

Some users might deem it advisable for a certain class of work to use a solid wheel. My improved construction is particularly adapted to be readily converted into a solid wheel by simply making the annular rim of wood and covering the same with leather, and also make the flanged edges 8 fill and fit snugly the grooves 9, which would effectually prevent the inward depression of the rim. For heavy work, the pneumatic tube may be used in place of the spiral spring.

Having thus described my invention, what I claim is:

1. A polishing wheel comprising an annular detachable rim, a spiral spring underlying the rim and in constant elastic contact therewith, and side plates between which the rim is adapted to have a free inward and outward movement.

2. A polishing wheel comprising an annu-

lar detachable rim adapted to carry abrasive material on its periphery, a spiral spring band underlying the rim and in constant elastic contact with the interior circumferential surface of the rim, side plates freely embracing the edges of the rim and spring band.

3. A polishing wheel comprising an annular detachable rim, a spiral spring band of multiple coils lying against the interior circumferential portion of the rim and in constant elastic contact therewith.

4. A polishing wheel comprising an annular rim formed of pliable material adapted to carry abrasive material on its periphery, a spiral spring band of multiple coils within the circumferential interior of the rim and in constant elastic engagement therewith, and side plates adapted to permit the inward movement of the rim and limit its outward movement.

5. A polishing wheel comprising an annular rim of pliable material adapted to carry abrasive material on its periphery, a spiral spring band of multiple coils lying against the interior circumferential surface of the rim and in constant elastic contact therewith, retaining side plates having a hub, and adjustable weights for balancing the wheel.

In testimony whereof I affix my signature in presence of two witnesses.

EDWARD D. WOODS.
